REVOLVER CARTRIDGE CLIP

Julius R. Pflaume, Berkeley, Ill.

Application February 1, 1933, Serial No. 654,611

4 Claims. (Cl. 42—89)

This invention relates to reloading devices for revolvers and particularly to a reloading cartridge clip.

The main objects of this invention are to provide an improved reloading cartridge clip for revolvers whereby all of the cylinder chambers may be simultaneously loaded; to provide such a cartridge clip from which all of the cartridges are simultaneously released by a single operation and inserted into the cylinder chambers of the revolver; to provide an improved cartridge clip of novel construction wherein the cartridges are positively locked against accidental release from the clip; and to provide a device of this character which is extremely durable and simple in its mechanical makeup, and which device may be readily attached to a cartridge belt or the like.

A specific embodiment of this invention is shown in the accompanying drawing in which:

Figure 1 is a perspective view showing a revolver held in the user's right hand and being loaded by means of the improved cartridge clip, user's left hand holding the clip being shown in dotted outline.

Fig. 2 is a sectional view of the cartridge clip showing cartridges positioned and held therein.

Fig. 3 is a view taken on line 3—3 of Fig. 2.

Fig. 4 is an enlarged sectional detail of a cartridge receiving tube showing the cartridge gripper in released position.

Fig. 5 is a perspective view of a cartridge gripper.

Fig. 6 is a fragmentary perspective view of a cartridge receiving tube showing the gripper grooves adjacent the inner end.

In the form shown in the drawing, the improved cartridge clip or reloader comprises a cartridge holder or container 1, embodying a series of cartridge receiving tubes 2 arranged in annular or circular formation and providing six cartridge chambers 3. While the holder 1 has been shown provided with six cartridge chambers, it will be understood that the number of cartridge chambers may vary in accordance with the number of cylinder chambers provided in the particular revolver for which the device may be intended.

As will be observed in Figs. 1 and 2, the holder 1 is proportioned so that the tapered ends of the cartridges 4 project slightly beyond the lower end of the holder when the cartridges are positioned and gripped or locked therein. Secured in the upper or inner end of each of the annular series of cartridge receiving tubes 2 is a car-

tridge stop or bumper 5 against which the bases of the cartridges 4 abut when slid into the chambers 3 and, as will be observed in Fig. 3, this stop or bumper 5, which is preferably of leather or other resilient material, traverses the axes of the tubes 2.

Mounted at the upper end of the holder 1 and secured to the upper or inner ends of the cartridge tubes 2 is a disc-shaped head plate 6 of a diameter equal to the greatest diameter of the holder 1. The head plate 6 serves to close off the inner ends of the cartridge tubes 2 and is provided with a centrally disposed boss 7 having a central aperture therein extending through the head plate 6.

Carried by and secured to the upper side of the boss 7, one for each of the cartridge receiving tubes 2, is a series of axially disposed spring cartridge clips or grippers 8 which engage or grip the rim 9 of the cartridges for holding the cartridges in the chambers 3.

The boss 7 is provided on its upper side with an annular groove 10 marginally surrounding the aperture, and positioned in the aperture is a gland-like holder and guide 11 having a cylindrical body extending below the head plate 6. The cylindrical body of the guide 11 is of a diameter substantially equal to the small diameter of the internal area between the cartridge tubes 2, as shown in Fig. 2, and is provided with a concentric axial bore 12. The guide 11 is also provided with an annular flange 13 having a diameter substantially the same as the boss 7 against which the flange is arranged to seat and where it is secured by means of screws 14.

The cartridge clips or grippers 8 are formed of spring metal and are flat bars having their ends turned at right angles so as to project from one side of the clip substantially as shown in Fig. 5. Adjacent one of the turned ends, the clip 8 is formed to provide a V-shaped projection or cam follower 15 extending from the clip on the side opposite the side from which the turned ends project.

The cartridge receiving tubes 2 are each provided with an aperture 16, positioned at the inner side of the annular series and located at a distance from the open end of the tube 2 substantially equal to the length of the shell of the cartridge 4. The side walls of each tube 2 are then grooved, as at 17 and 18 in Fig. 6, in the portion between the aperture 16 and the inner or closed end of the tube 2. The grooves 17 and 18 are cut in the tube wall so that their deepest parts are at the opening 16 and the inner end

respectively, the grooves tapering or growing more shallow as they approach each other until they fade or disappear entirely half way between the opening 16 and the inner end of the tube 2.

5 The spring clips or grippers 8, which have a length between their bent ends substantially equivalent to the distance from the center of the aperture 16 in the cartridge tubes 2 to the bottom of the groove 10 in the boss 7 of the head plate 10 6, are disposed in the cartridge holder in an axial position, each with the bent end or finger 15 adjacent the projecting portion or cam follower 15, extending through the aperture 16 and providing a catch for engaging the rim of a cartridge. The opposite bent end 20 of each gripper is positioned in the annular groove 10 of the boss 7 and the body of the gripper is disposed substantially within the groove 18. The spring clips or grippers 8 are secured in this 20 position by means of the holder or guide 11 which clamps the body of each spring clip in a respective groove 18 and whose flange 13 clamps the projecting ends 20 in the annular groove 10 of the boss 7. Thus the spring clips 8 in their 25 normal position are not parallel to the axis of the cartridge holder but converge inwardly toward the axis thereof.

30 A plunger means is provided to actuate the spring clips so that they will simultaneously grip or release the cartridges from the cartridge receiving tubes. This plunger means comprises a stem 21 which extends through and is slidable in the bore 12 of the holder or guide 11. The lower end of the stem 21 extends axially into the holder between the tubes 2 and secured to the upper end of the stem 21 is a suitable thumb-engaging cap or knob 22 by which the plunger stem is manipulated inwardly or outwardly.

40 Fixedly secured to the inner end of the stem 21 and within the space between the annular series of tubes 2 is a pair of spaced cams or release members 23 and 24, comprising cylindrical enlargements of the stem 21 and arranged to be selectively engageable with the projections 15 of the fingers or grippers 8. Upon engaging the projections 15, the respective cam 23 or 24 forces the spring clips or grippers 8 outwardly relative to the axis of the holder and into the respective grooves 17, so that each finger or catch 19 projects through a respective aperture 16 and into the respective cartridge receiving chamber 3. Each spring clip 8 is thus fulcrumed on the grooved side wall of the tube 2 at the point 25 where the grooves 17 and 18 meet and disappear or fade.

45 In the operation of my improved cartridge holder, the device is loaded by first positioning the plunger 21 so that the projection or cam follower 15 of each spring clip 8 is released into the space between the cams 23 and 24, thus permitting the spring clips to assume their normal inwardly converging position and leaving the cartridge receiving chambers 3 clear of the fingers or catches 19 for the insertion of the cartridges 4, as shown in Fig. 4.

50 The cartridges are inserted singly into their respective tubes while the holder is held in an inverted position. The fall of the cartridges is cushioned by the resilient bumper 5 disposed at the inner end of the tubes, so that there is no danger of the shells being exploded by any metal-to-metal impact upon their bases.

55 After all of the receiving chambers have been loaded, the plunger 21 is moved outwardly until

the cam 23 engages the projections or cam followers 15 on the spring clips or grippers 8. Thus the fingers or catches 19 of the grippers 8 are forced into the cartridge receiving chambers 3, as shown in Fig. 2, where they are engaged by the rims 9 of the cartridges 4. In this manner the cartridges will be firmly held in the holder and will not be released until an inward pressure is exerted on plunger stem 21, in order to move the cam 23 away from the projections 15 of the grippers 8 and allow the grippers to spring back to their normal position and release the shells.

60 When reloading a revolver, the revolver cylinder is first swung from the revolver and the empty shells ejected. The reloader is then placed above the revolver cylinder with the tapered ends of the cartridges projecting into the chambers in the cylinder. The plunger stem 21 is then forced inwardly, whereupon all of the cartridge grippers 8 will be released and the cartridges permitted to fall into the revolver cylinder. Thus it will be seen that all of the revolver cylinder chambers are loaded simultaneously and by one operation.

65 As shown in Fig. 2 of the drawing, my improved reloading device is provided with two gripper operating cams; namely, the cams 23 and 24. The cams 23 and 24 are spaced apart on the stem 21 so that there is ample space between them to permit the grippers 8 to assume their normal position wherein the fingers 19 are withdrawn 105 from the cartridge chambers 3.

70 The length of the cylindrical body of the guide and holder 11 is such that when the cam 24 is abutting against its inner end, the cam 23 will be positioned exactly opposite the cam followers 110 15 of grippers 8. With this arrangement of cams, and when the holder or reloading device 1 is completely filled with cartridges the plunger 21 may be pushed into the device so that the cam 24 will engage the followers 15 of the grippers, the length of the stem 21 being preferably such that when the cam 24 is in this position the knob or thumb cap 22 will be abutting the upper flange 13 on the guide 11. Thus the cartridges will be gripped and locked within the holder and the plunger 21 will be in such a position that the cartridges cannot be inadvertently released when the reloader is carried in the user's pocket or in a cartridge belt designed for its reception.

75 When it is desired to reload a revolver, the reloader is inverted so that the cartridges are pointing upwardly and the plunger 21 is then withdrawn from the holder until it is stopped by the abutment of the cam 24 against the inner end of the guide 11. This will move the cam 23 into a position wherein the cartridges are still locked within their respective chambers and the reloader is then used in the manner that has been heretofore mentioned.

80 From the foregoing, it will be seen that an improved reloading clip for revolvers has been provided, whereby all of the chambers in a revolver cylinder may be simultaneously loaded with cartridges by merely pressing a plunger stem which acts to release a series of cartridge grippers simultaneously, each gripper individually holding a respective cartridge.

85 The construction of the device also prevents a possible accidental firing of the cartridges, since the bases of the cartridges are fully protected and no metal-to-metal impact is made thereupon, either during loading of the device or while the cartridges are being carried by the user as a reseive supply.

90 Although but one specific embodiment of this invention is herein shown and described, it will be 150

understood that details of the device shown may be altered or omitted without departing from the spirit of this invention as defined by the following claims.

5 I claim:

1. In a reloading cartridge clip for revolvers, a holder having an annular series of cartridge receiving chambers, a head plate, grippers carried by the head plate one for each of said chambers, 10 said grippers each comprising an arm disposed parallel with the holder and having a finger for engaging the base of a cartridge, a plunger stem mounted axially in said head plate and extending axially of the holder, and a cam on said stem engageable with the gripper arms to simultaneously 15 actuate the same for causing the fingers thereof to be engaged and disengaged from the cartridges.

2. In a reloading cartridge clip for revolvers, a holder having an annular series of cartridge receiving chambers, a head plate, grippers carried by the head plate one for each of said chambers, 20 said grippers being arranged in parallel relation and each comprising a laterally projecting finger and an oppositely extending cam follower, 25 said finger being arranged for engaging the base of a cartridge inserted into a respective chamber, a plunger stem reciprocally mounted axially of the head plate, and a cam mounted on said stem and disposed centrally in the holder for engaging the cam followers on said grippers, said cam actuating the gripping fingers upon movement of the plunger stem.

3. In a reloading cartridge clip for revolvers, 30 a holder having an annular series of cartridge

receiving chambers, a head plate, a gripper adjacent the inner end of each cartridge chamber, means securing the grippers to the head plate by their end portions and with the grippers in axially arranged relation, said grippers each comprising an arm having a laterally projecting catch extending into a respective cartridge chamber and arranged to engage the base of a cartridge, a cam disposed centrally between the arms of the grippers, and a plunger stem reciprocable in the head plate and having guided movement between the cartridge chambers, said cam being mounted on said plunger stem and arranged to simultaneously actuate the grippers upon movement of the plunger stem.

4. A reloading cartridge clip for revolvers comprising in combination, a cartridge holder embodying a series of annularly arranged tubes providing cartridge receiving chambers, said tubes having an aperture in their inner walls intermediate their ends, a head plate, a series of grippers secured to the head plate one for each of said tubes, said grippers each comprising an axially extending arm having a projecting finger extending into the wall aperture of a respective 100 tube, a cam following projection on each of said arms disposed adjacent the finger and on the opposite side thereof, a centrally disposed cam arranged to engage said cam following projections, and a plunger stem movable axially through 105 the head plate and being connected to the cam for movement thereof for simultaneous actuating of all of the grippers.

JULIUS R. PFLAUME.
